DESIGN FOR A SHOWER CURTAIN RING

Charles E. Stephenson, New York, N. Y., and Herbert D. Schmidt, Little Falls, N. J., assignors to R. D. Werner Co., Inc., New York, N. Y., a corporation of New York

Application January 15, 1946, Serial No. 125,578

Term of patent 3½ years

(Cl. D21—1)

To all whom it may concern:

Be it known that we, Charles E. Stephenson and Herbert D. Schmidt, both citizens of the United States of America, and residing respectively at New York city, in the county and State of New York, and at Little Falls, in the county of Passaic and State of New Jersey, have invented a new, original, and ornamental Design for a Shower Curtain Ring, of which the following is a specification, reference being had to the accompanying drawing, forming a part thereof.

Fig. 1 is a front elevational view of a shower curtain ring, showing our new design.

Fig. 2 is a side view thereof.

We claim:

The ornamental design for a shower curtain ring, substantially as shown.

CHARLES E. STEPHENSON.
HERBERT D. SCHMIDT.
